UNITED STATES PATENT OFFICE.

GEORGE F. FREED, OF BEN AVON, PENNSYLVANIA, ASSIGNOR TO PITTSBURGH GAGE & SUPPLY COMPANY, OF PITTSBURGH, PENNSYLVANIA, A CORPORATION OF PENNSYLVANIA.

DRIVING CONNECTION TO WASHING-MACHINE CYLINDERS.

1,337,552.

Specification of Letters Patent. Patented Apr. 20, 1920.

Application filed March 24, 1919. Serial No. 284,550.

To all whom it may concern:

Be it known that I, GEORGE F. FREED, a resident of Ben Avon, in the county of Allegheny and State of Pennsylvania, have invented a new and useful Improvement in Driving Connections to Washing-Machine Cylinders, of which the following is a specification:

This invention relates to improvements in 10 washing machines of the cylinder type, and particularly to the means for removably supporting the cylinder in the tub and connecting it with the member for rotating said cylinder.

15 Washing machines of the cylinder or drum type usually have the cylinder or drum removably supported in the tub and operatively connected to the rotating means in a manner to permit the cylinder to be disconnected from the rotating means and removed from the tub by tilting the cylinder and then lifting it out of the tub. In removing the cylinders from the tub, and again replacing them therein, in this manner, it frequently 25 happens that the cylinders become jammed and mutilated to such an extent that a new cylinder must be supplied.

The object of the present invention is to 30 provide an arrangement of parts which permits the cylinder or drum to be lifted out of the tub with a straight rectilinear motion, without tilting, and therefore without liability of jamming or mutilating the cylinder; and which means provide for automatically and securely locking the cylinder in 35 operative relation to its rotating means.

In the accompanying drawing Figure 1 is 40 a vertical sectional view taken longitudinally through the cylinder and through the end walls of the tub and showing the mounting of the cylinder and its operating connection with the rotating means; Fig. 2 is a vertical sectional view on the line 2—2, Fig. 1, showing only the means for connecting 45 the cylinder to its rotating means; and Fig. 3 is a central vertical section through the parts shown in Fig. 2.

In the drawing 1 and 2 represent the end walls of a suitably shaped tub, in which is 50 the rotary cylinder 3. The lower end of a hanger or socket 4 attached to one end wall of the tub and open at its top forms a bearing for the journal or trunnion 6 attached to the adjacent end of the cylinder 3. This

arrangement permits the cylinder to be 55 lifted out of the tub.

Extending through the opposite end wall 2 of the tub is a rotatable shaft 7, which may be either hand or power driven, preferably the latter, and, which preferably is connected to automatic reversing mechanism to periodically reverse the cylinder or drum, as is well known in this type of machine. On the inner end of this shaft is the driving arm 8, having substantially parallel side 60 edges, and provided at its end on its outer face, that is, the face toward the wall 2 of the tub, with a transverse shoulder 10, and beyond the same with the beveled face 11. Secured to the adjacent end of the cylinder 65 or drum is a clutch member having a web portion 12 provided with holes 13, for receiving counter-sunk screws, rivets, or small bolts, for securing the same to the cylinder, and being provided with parallel flanges 15 70 spaced apart a distance slightly greater than the width of the driving arm 8 and adapted to receive the driving arm therebetween, said flanges at their free ends curving outwardly, as at 16, to provide a flaring entrance to 75 guide the clutch onto the driving arm. Preferably the side flanges 15 are provided near their lower ends (that is, the ends which are lowermost when the cylinder is in 80 position to be removed from the tub) with a bridge piece 17 which lies outside of the driving arm, as shown, and serves as a means to prevent displacement of the cylinder endwise relative to the driving arm. Near their 85 opposite ends said flanges are connected by a transverse web 18 serving as a limiting stop against which the end of the driving arm contacts when the parts are assembled; and beyond this are provided with a pair of 90 perforated bosses 19 for receiving the pivot or trunnion 20 of a locking latch 21 which on the inner face of its lower end is provided with a hook 22, and beyond this with a beveled face 23. A compression spring 24 is interposed between the upper end of the latch 95 and the clutch member, being seated at one end in a socket 25 in the latch and at its other end over a stud or boss 26 on the clutch member. The extreme upper end of the latch is flattened and widened to form the 100 handle portion 27.

The parts are shown in assembled relation, in which the driving arm 8 on the shaft 7

projects up into the groove between the side flanges 15 of the clutch member, with its upper end in contact with the transverse web 18, and being locked to said clutch member by means of the hook 22 on the latch 21 engaging over the shoulder 10 of the driving arm. By this means the drum is securely locked to the driving member, and cannot become detached therefrom during its rotation.

10 When it is desired to remove the cylinder from the tub, the parts will be brought to a state of rest (preferably by the automatic reversing means) with the driving arm 8 standing vertically. Then, by merely taking hold of the cylinder at opposite ends, and with the fingers of one hand pressing inwardly on the handle 27 of the latch, the hooked lower end thereof is disengaged from the shoulder or hook portion 10 of the driving arm, whereupon the drum can be lifted out of the tub in a straight rectilinear line. To replace the drum, it is merely lowered down into the tub while the driving arm is vertical, thus causing the flared lower ends 16 of the clutch flanges to guide the parts into proper connecting relation, the mere downward movement of the drum causing the beveled face 23 on the latch to slide past the beveled face 11 on the driving arm, and causing the latch to automatically interlock with the driving arm, as will be obvious.

15 The construction described provides for removing the drum from the tub, and again replacing the same therein, in straight rectilinear lines, thus obviating any danger of jamming or mutilating the cylinder. The drum is securely locked to the rotating member and in a manner which permits of its 20 ready unlocking therefrom, and to permit its automatic interlocking therewith.

I claim:

1. In a washing machine, the combination with a tub, of a cylinder therein, detachable bearings at one end of the cylinder and tub, an operating shaft extending through the opposite end of the tub, a driving arm on the inner end of said shaft, and a clutch member on the adjacent end of the cylinder including a socket open radially of the cylinder to receive said driving arm, and spring actuated means to automatically lock said arm to said clutch member.

2. In a washing machine, the combination

with a tub, of a cylinder therein, detachable 55 bearings at one end of the cylinder and tub, an operating shaft extending through the opposite end of the tub, a driving arm on the inner end of said shaft, and a clutch member on the adjacent end of the cylinder 60 comprising a socket to receive said driving arm and a pivoted spring-actuated latch for locking the driving arm to said clutch member, said driving arm and latch being provided with interlocking shoulders and bevelled faces to permit automatic interlocking 65 of said shoulders.

3. In a washing machine, the combination with a tub, of a cylinder therein, detachable bearings at one end of the cylinder and tub, 70 an operating shaft extending through the opposite end of the tub, a driving arm on the inner end of said shaft, a locking shoulder on said arm, a clutch member 75 on the adjacent end of the cylinder and provided with a flaring open sided socket to receive said driving arm, and a spring-actuated latch having a hooked portion to engage the shoulder on said arm.

4. In a washing machine, the combination 80 with a tub, of a cylinder therein, detachable bearings at one end of the cylinder and tub, an operating shaft extending through the opposite end of the tub, a driving arm on the inner end of said shaft, a clutch member 85 on the adjacent end of the cylinder including a socket open radially of the cylinder to receive the said driving arm and a bridge member to prevent endwise movement of the cylinder, and means to lock said arm to said 90 clutch member.

5. In a washing machine, the combination with a tub, of a cylinder therein, detachable bearings at one end of the cylinder and tub comprising a socket open radially of the cylinder, 95 an operating shaft extending through the opposite end of the tub and provided on its inner end with a driving portion, a clutch member on the adjacent end of the cylinder including a socket open radially of the cylinder to receive the driving end of said shaft, and a spring-actuated latch for locking said driving shaft in said socket.

In testimony whereof, I have hereunto set my hand.

GEORGE F. FREED.

Witness:

ALICE A. TRILL.
